INTERRUPTED STRIPE PAINTING MACHINE

Donald H. Clark, Sacramento, Calif.

Application July 24, 1942, Serial No. 452,162

13 Claims. (Cl. 91—12)

This invention relates to a machine for applying a paint stripe to a highway, and particularly to one for applying paint in the form of an interrupted rather than a continuous stripe, and which results in a considerable saving of paint.

The principal object of my invention is to provide a mechanism for the purpose by means of which an interrupted stripe of predetermined section lengths and spacing will be automatically painted on the road with the movement of the machine along the same.

In connection with the stripe application or painting, glass beads are frequently applied on the stripes at intervals, the bead dispenser being mounted on the same machine as the paint applicator, in trailing relation thereto; the dispenser functioning automatically with the advance of the machine.

A further object of this invention is to arrange and control the operation of the bead dispenser so that such operation will be automatically halted while passing over the unpainted spaces or interruptions between the stripe sections, but will be resumed as soon as the stripe painting is resumed. Here again a considerable saving in beads and a resultant saving in expense is effected.

It is necessary at intervals to apply paint over an old striping, and another object of the invention is to provide control means for the paint gun actuating mechanism so arranged that the new stripe may be accurately superimposed over the old one without any overlap at either end.

The machine is mounted on pneumatic-tired wheels, the rotation of which controls the functioning of the paint control mechanism, which is designed to give a predetermined paint-stripe length and spacing with wheels of a predetermined operating diameter. If the effective wheel radius or diameter varies, due to variation in tire inflation or weight of the operator on the machine, the operation of the paint control mechanism will thus likewise vary. It is therefore another object of the invention to arrange the paint control mechanism so as to enable the functioning of the same to be compensated for any such variation in wheel diameter, so as to enable the paint stripe sections to be maintained at such predetermined length and spacing.

Other objects of the invention will be apparent from a perusal of the following specification.

In the drawings similar characters of reference indicate corresponding parts in the several views:

Figure 1 is a side elevation of a stripe painting

machine as in operation, the conduits leading to the paint spray gun and bead dispenser cylinder being shown somewhat diagrammatic, and only those conduits which are essential to an understanding of the invention being shown.

Figure 2 is a fragmentary enlarged side elevation showing the driving and control mechanism for the air supply control valve.

Figure 3 is a fragmentary top plan view of the machine showing the mechanism depicted in Fig. 2.

Figure 4 is a fragmentary top plan showing the mounting of the bead dispenser and its associated air lift cylinder and brake.

Figure 5 is a fragmentary side elevation showing the bead dispenser, air lift cylinder, and brake unit.

Figure 6 is a front view of the control valve unit, with the cover plate removed, and with the valve rotor in the position occupied when at the outset of a painting operation.

Figure 7 is a sectional plan of the valve substantially on the line 7—7 of Figure 6.

Figure 8 is a view similar to Fig. 6, but showing the valve rotor as positioned at the start of an air-exhausting movement from the paint guns, or when the painting operation is halted.

Figure 9 is a sectional plan of the valve substantially on the line 9—9 of Figure 8.

Figure 10 is a fragmentary front view of the cover plate of the valve partly in section.

Referring now more particularly to the characters of reference on the drawings, the machine comprises a horizontal frame structure 1 supported at its rear end by a pair of pneumatic-tired wheels 2 and at the front end by a pair of steerable wheels 3. Steering of the latter is controlled from a steering wheel 4 mounted on the frame convenient to the operator's seat 5, also mounted on the frame adjacent its rear end. The machine is not self-propelled, but is adapted to be pushed ahead by a vehicle attached to a rear end clevis 6 on the machine, such vehicle, as usual, having a paint supply and air compressing unit thereon.

A number of paint spray guns 7 are supported in fixed connection with the rear end of an arm unit 8 which extends forwardly to pivotal connection with the frame 1, as at 9, so that the guns may give vertically and also be lifted clear of the road; such lifting being effected by any suitable means, such as a lever and link mechanism, indicated at 10.

The guns are of a standard type commonly used in highway striping work, the feeding of

the paint onto the road from each gun taking place only upon the opening of a needle valve 11 in the gun, and such needle valve is opened upon admission of compressed air from a conduit 12 leading to a cylinder 13 at the top of the gun, and to the piston rod of which gun the needle valve is connected.

Disposed between the wheels 2 rearwardly of the gun unit is a bead dispenser 13, also of standard type and supported on road-engaging wheels 14, the rotation of which controls the dispensing of the beads in predetermined quantity. The dispenser is pivoted at its forward end in connection with the frame 1, as at 18, so that it may be swung vertically and lifted clear of the ground; and such lifting is effected by the admission of air pressure from a conduit 16 to an air cylinder 17 hung on a frame-mounted crossbar 18 above the dispenser and whose piston rod 19 is connected to the dispenser at its rear end.

The above type of road-striping machine and the general arrangement of parts, except for the dispenser lift device, is standard equipment, and I do not change the same. The flow of air to the paint gun, however, is ordinarily hand-controlled, whereas I apply an automatically functioning control means as follows:

Secured on one wheel is a friction drum 20 normally engaged by a relatively light but large-diameter pneumatic-tired wheel 21. The axis of this wheel is above the axis of the wheel 2 and is supported between outer and inner arms 22 and 23 which are pivotally supported in common in connection with the frame 1 forwardly of the wheel 21, as shown at 24.

The inner arm 23 projects rearwardly of the wheel 21 some distance and is formed at its rear end with a substantially horizontal ear 25 through which a threaded rod 26 projects; said rod being maintained in a fixed position relative to the ear by counteracting springs 27 on the rod above and below the ear. The rod above the ear is threaded through a block 28 which is swivelly supported, as at 29, on a longitudinal extending lever 30 intermediate the ends of the latter, the lever being disposed to one side of and convenient to the operator on the seat 5, as shown in Fig. 1. This lever is pivoted at its forward end on a standard 31 upstanding from the frame 1, and cooperates with a two-position quadrant 32 on the standard, arranged so that when the lever is lowered, the wheel 21 engages the drum 20, and when said lever is swung up the wheel is well clear of the drum.

The upper end of the rod has a hand wheel 33 thereon for turning the rod, and it will be seen that upon thus turning the rod the arm 23 and consequently the wheel 21 will be raised or lowered relative to the drum, and the direct distance between the centers of the wheels 2 and 21 will be altered so as to alter the effective diameter and circumferential extent of the wheel 21. When doing this, the tire of said wheel of course yields in order to enable this difference in effective wheel radius or diameter to be obtained. A fixed pointer 34 on the standard 31 cooperates with the ear 25 and provides a period adjustment gauge or marker.

Secured on the arm 22 intermediate its ends is a valve housing 35 which, for convenience of manufacture, includes a back member 36, a central ring 37 and a front cover plate 38; the enclosed space between said members forming a valve chamber in which the valve rotor is turnable. This rotor includes an outer valve disc 39

and an inner valve disc 40 rotatable with the disc 39 as a unit, but circumferentially adjustable relative thereto. A drive shaft 41 is secured to the disc 40 and is driven from the wheel 21 by a speed reduction chain drive 42.

A compressed air supply pipe 43 is connected with a port 44 in the cover plate 38, which port is in the zone of the outer valve disc 39; while a passage 45 in the back member 36, and to which the conduit 12 is connected, terminates in facing relation to the port 44. A pair of opposed circumferential slots 46 in disc 39 alternately establish communication between the port 44 and passage 45. Between the slots the disc 39 is provided with circumferential bypass passages 47 which alternately establish communication between the passage 45 and a discharge or relief port 48 in the periphery of the valve housing ring 37.

20 The valve disc 39 therefore has two complete cycles of operation for each single revolution of the valve; each cycle comprising an interval during which a slot 46 is in communication with the port 44 and passage 45 and air is flowing through the conduit 12 to actuate the needle valve of the spray gun and allow the paint to flow; and a succeeding interval during which the port 44 is shut off but communication is established between the passage 45 and the port 48 through bypass 47, exhausting air from the needle valve and causing the latter to close and the painting to be discontinued. The slots 46 and bypass passages are here arranged, in connection with the chain drive 42 and the wheel drum and drum ratios, to cause a fifteen-foot stripe to be painted, followed by a twenty-five foot unpainted section, but such proportions may obviously be varied by a change in the proportion of one or the other of the various parts.

40 Since such distances, which are obtained with a corresponding travel of the machine along the road, are based upon a certain predetermined diameter of the wheel 2, any change in the effective diameter and circumferential extent of such wheel, such as is caused by under or over tire inflation, tire compression, etc., will affect the extent of rotation of the valve rotor over a given distance of travel of the machine along the road. For this reason, the compensating or adjusting device for the wheel 21, as previously described, is provided, so that the effective diameter of said wheel may be altered while the machine is in motion if desired or necessary to counteract any change in the effective diameter of the wheel 2.

45 The inner valve disc 40 is also provided with opposed circumferential slots 49 which are adapted one at a time to establish communication between an air intake passage 50 provided in the cover plate 38 in communication with the inlet port 44, and a passage 51 in the member 36 to which the bead dispenser lift cylinder conduit 16 is connected. Between the slots 49 the disc 40 is provided with bypass passages 52 registering at one end with one end of radial passages 53 in the disc 39.

50 The other end of each passage 52 registers with the passage 51 at the same time that the other end of the corresponding passage 53 registers with an outlet or relief port 55 in the periphery of the ring 37.

55 As soon as the bead dispenser is set back of the paint gun the former should start (by being lowered upon the release of air from cylinder 17) a predetermined and proper time after or before

the stripe painting is begun. The bypass passage 52 in the disc 40, and which controls the release of air from the cylinder 17, are therefore set back the proper distance from the slots 48 in the outer disc 39 and which control the flow of air to the paint gun. This distance may be accurately controlled or adjusted by turning the valve disc 40 relative to the disc 39 upon suitable manipulation of the driving set screw 56 which connects the discs. (See Fig. 6.)

In order that the valve as a whole may be properly set at the outset of a painting operation, a gauge finger 57 is mounted on the arm 22 and is adapted to read against one at a time of a pair of opposed pins 58 on the adjacent sprocket wheel 42a of the chain drive 42 (see Fig. 3). At the outset of an operation, the wheel 21 is turned by hand, if necessary, to dispose the pointer in register with either pin, and when in this position the valve is about in position to initially admit air to the paint gun cylinder to start the flow of paint.

This arrangement makes possible the accurate synchronization of the valve with the point of beginning of the painted portion of a stripe, when a restriping job is being done.

When the bead dispenser is raised, it is desirable that the timing of the bead dispensing, which is controlled by rotation of the wheels 14, shall not be disturbed. I therefore provide a flat brake strip 60 above one wheel 14 in position to be engaged thereby when the dispenser is lifted (see Fig. 5). This strip is pivoted intermediate its ends on a horizontal axis, on a vertical stem 61 turnable in brackets 62 projecting from the adjacent portion of frame 1. This stem is normally prevented from rotation by a releasable holding pin 63 between the stem and a quadrant formed on the upper bracket 62 (see Fig. 4). A tension spring 64 between the free end of the strip 60 and the stem resists upward movement of said strip. Rotation of the stem, which causes the brake strip to swing also, is necessitated by reason of the fact that the bead dispenser is, as usual, arranged for lateral adjustment on the machine to one side or the other of a normal central plane, as the lateral position of the stripe being painted may require. By the means above described the brake strip may be disposed directly above the wheel 14 in operating relation thereto, regardless of the lateral position of the dispenser to one side or the other of its normal central plane.

While this machine has been particularly designed to control highway stripe painting operations, said mechanism may be used for other purposes for which it may be found suitable.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. In a road striping machine which includes a paint applying device and a bead dispenser rearwardly of said device; separate control mechanisms for said device and dispenser mounted on the machine, actuating means for the control mechanisms, and means controlling said actuating

means and functioning upon forward travel of the machine to place said actuating means in operation to cause the device and dispenser to operate one after the other and for a common period, and to then cause the operation of the device and dispenser to discontinue one after the other and for another common period.

2. In a road striping machine which includes a paint applying device and a bead dispenser rearwardly of said device; means to control the operation of the device, means to control the operation of the dispenser and a mechanism mounted on the machine and functioning upon forward travel thereof and connected to the device and dispenser control means to control the functioning of said device control means and dispenser control means in predetermined and successive order.

3. A structure as in claim 2, with means to render said mechanism inoperative at will and irrespective of travel of the machine.

4. In a road striping machine which includes a paint applying device and a bead dispenser rearwardly of said device; means to control the operation of the device, means to control the operation of the dispenser, a mechanism mounted on the machine and connected to the device and dispenser control means to actuate the same, and means operated by forward movement of the machine to actuate said mechanism to first cause the device to be placed in operation, to then cause the dispenser to be placed in operation after the device has painted a stripe of a length approximately equal to the horizontal spacing of the device from the dispenser, to subsequently and after a predetermined period to cause the operation of the device to be discontinued and after a further advance of the machine a distance substantially equal to said spacing to cause the operation of the dispenser to be discontinued.

5. In a material feeding machine adapted for movement along the ground and having a feeding device including means placing said device in operation by the feeding of fluid under pressure thereto, a friction drum, means to rotate the drum upon movement of the machine along the ground, a wheel yieldable at its periphery engaging the drum, a support on which the wheel is mounted, a rotary control valve for the fluid supply of the device mounted on the support, means to drive the valve by the wheel and means to adjust said wheel relative to the drum to alter the effective radius of the wheel.

6. In a material feeding machine adapted for movement along the ground and having a material feeding device including means placing the device in operation by the feeding of fluid under pressure thereto, a rotary element on the machine, means to rotate the element upon movement of the machine along the ground, another rotary element frictionally engaging the first named element, one of said elements being radially yieldable at its periphery, a rotary control valve for the fluid supply of the device, means to drive the valve by said other rotary element, and means operatively connected to one element to alter the straight line distance between the centers of the elements.

7. A structure as in claim 5, with separate means to move the wheel clear of the drum without affecting the wheel adjustment means.

8. In a material feeding machine adapted for movement along the ground and having a material feeding device including means placing the device in operation by the feeding of fluid under

pressure thereto, a friction drum, means to rotate the drum upon movement of the machine along the ground, a wheel yieldable at its periphery engaging the drum, an arm on which the wheel is mounted, means pivoting the arm on the machine at a point such that the axis of the wheel is normally clear of a direct line between the drum and pivot axes, a rotary control valve for the fluid supply of the device mounted on the arm, means to drive the valve from the wheel, and means connected to the arm to swing the same through a limited arc.

9. In a material feeding machine adapted for movement along the ground and having a material feeding device including means placing the device in operation by the feeding of fluid under pressure thereto, a friction drum, means to rotate the drum upon movement of the machine along the ground, a wheel yieldable at its periphery engaging the drum, an arm on which the wheel is mounted, means pivoting the arm on the machine beyond the side of the wheel opposite the drum, a rotary control valve for the fluid supply of the feeding device mounted on the arm, means to drive the valve from the wheel, and means operatively connected to the arm to swing the same in a direction to disengage the wheel from the drum.

10. In a material feeding machine adapted for movement along the ground and having a material feeding device including means placing the device in operation by the feeding of fluid under pressure thereto, a friction drum, means to rotate the drum upon movement of the machine along the ground, a wheel yieldable at its periphery engaging the drum, an arm on which the wheel is mounted, means pivoting the arm on the machine at a point such that the axis of the wheel is normally clear of a direct line between the drum and pivot axes, a rotary control valve for the fluid supply of the feeding device mounted on the arm, means to drive the valve from the wheel, means to swing the arm through a limited arc and including a rod connected to and

substantially at right angles to the arm and a block through which the rod is threaded and means supporting the block for movement between different positions lengthwise of the rod.

11. A structure as in claim 10, in which said last named means comprises a lever pivoted at one end on the machine and extending crosswise of the rod, the block being mounted on the lever and means to hold the lever at either one of two swung positions.

12. In a material feeding machine adapted for movement along the ground and having a material feeding device including means placing the device in operation by the feeding of fluid under pressure thereto, a rotary element, means to rotate the rotary element upon movement of the machine along the ground, another rotary element frictionally engaging the first named element, one of said elements being radially yieldable at its periphery, a rotary control valve for the fluid supply of the feeding device, means to drive the valve by the other rotary element, a rotary member fixed with the valve exteriorly thereof, a marker element on said member and a fixed pointer to read against the marker; the latter being disposed relative to the valve so that when the pointer reads against the marker, the valve is approximately in position to open and supply fluid to the device.

13. In a material feeding machine adapted for movement along the ground and having a feeding device including means placing said device in operation by the feeding of fluid under pressure thereto, a rotary element on the machine, means to rotate the element upon movement of the machine along the ground, another rotary element frictionally engaging the first named element, a rotary control valve for the fluid supply of the device, means to drive the valve by said other rotary element and means to alter the rate of rotation of the valve relative to that of the first named element.

DONALD H. CLARK.
